UNITED STATES PATENT OFFICE.

FRANCES AYRES RODDY, OF NEW YORK, N. Y.

EDUCATIONAL DEVICE.

1,385,096.

Specification of Letters Patent. Patented July 19, 1921.

Application filed October 21, 1920. Serial No. 418,439.

To all whom it may concern:

Be it known that I, FRANCES AYRES RODDY, a citizen of the United States, and resident of the borough of Manhattan, city, county, 5 and State of New York, have invented certain new and useful Improvements in Educational Devices, of which the following is a specification.

My invention relates to educational devices and has for its object to provide a device of novel construction and arrangement whereby knowledge of elementary characteristics may be imparted to children in a simple and interesting manner. My invention contemplates a construction which 10 may be readily set up for use and which may be easily and compactly folded when not in use. Other more specific objects of my invention will appear from the description 15 hereinafter and the features of novelty will be pointed out in the appended claims.

In the accompanying drawings which illustrate an example of my invention without defining its limits, Figures 1 and 2 are 20 side and front views respectively of the device in a folded condition; Figs. 3 and 4 are similar views respectively, showing the device in an unfolded position ready for use; and Figs. 5 to 8 inclusive illustrate examples 25 of the members or blocks which constitute a part of the device.

As shown in the illustrated example, the device is constructed in the form of a foldable frame or ladder consisting of two sections 30 10 and 11 hinged together at 12 and provided with a prop 13 of suitable form and construction hinged at 14 to the section 10 whereby the ladder is supported in an operative position, preferably inclined, as 35 shown in Figs. 3 and 4. One or more, and preferably a pair of latches 15, may be included in the construction for fixing the sections 10 and 11 in their unfolded operative positions. A plurality of rungs 16, prefer- 40 ably though not necessarily of cylindrical cross-section, are mounted upon the sections 10 and 11 in spaced, parallel relation and so as to be removable at will, any convenient means being provided for maintaining the 45 rungs 16 against unintentional removal from the sections 10 and 11 or frictional engagement of the parts alone being relied upon to prevent the same. The sections 10 and 11 50 comprise jointed side members and the rungs 16, or some of them, constitute transverse members which coöperate with said side

members to hold the same in spaced relation to each other. To facilitate manipulation, the rungs 16 may be made of sufficient length to project beyond either one or both side 60 members of the sections 10 and 11, for instance, as illustrated in the drawings. The device comprises further a plurality of preferably cubical blocks or members 17 having apertures 18 extending therethrough, where- 65 by said blocks or members are adapted for mounting upon the rungs 16. Those faces of the cubical blocks 17 which extend parallel to the apertures 18 are provided with letters of the alphabet, numerals, pictorial 70 representations of various kinds, such, for instance, as are commonly associated with well known nursery rhymes or any other devices or designations, all of which may be produced upon said surfaces in any conven- 75 ient and well known way. The blocks or members 17, when mounted or strung upon the rungs 16 are slidable lengthwise thereof and rotatable thereon, but preferably en- 80 gage said rungs with sufficient friction to remain fixed in any position to which they may be adjusted.

In utilizing the device it is brought from the folded position shown in Figs. 1 and 2 to the unfolded position illustrated in Figs. 85 3 and 4 and set up, as shown, in any convenient location so as to be within easy reach. The device may be used for teaching the letters of the alphabet and numerals, for constructing sentences, for word building, 90 for familiarizing the child with the well known nursery rhymes and for dissected pictures. That is to say, the blocks 17 may be strung or mounted upon the rungs 16 either individually or collectively to provide 95 any desired combination of letters, numerals or pictorial groups. For instance, as shown in Fig. 4, three blocks 17, with letters of the alphabet thereon, may be ar- 100 ranged in horizontal sequence upon a rung 16 to spell the word "cat;" similarly three blocks 17 also with letters of the alphabet thereon may be arranged individually upon adjacent rungs 16 in vertical sequence to spell the word "tar." The terminal or any 105 other of the horizontal group of blocks may be utilized for combination with the vertical group of blocks to complete a word so that the two words are formed as indicated, for instance, in Fig. 4. Any other word or 110 words or groups of words may be similarly constructed by simply arranging the blocks

in proper sequence; groups of numerals may be formed in the same way. The blocks 17 may be also arranged in pictorial groups; for instance, blocks portraying various types 5 of soldiers may be arranged as in Fig. 6, while the representation of a locomotive and train of cars may be set up by arranging the proper blocks as in Fig. 7. The well known nursery rhymes may be visualized by stringing 10 the proper blocks 17 upon a rung 16, for instance, as illustrated in Fig. 8 and likewise various other combinations may be effected in a manner which is interesting to the child and which conveys the knowledge 15 in a simple manner easy to understand, the device being capable of use by the children themselves as a toy.

The invention provides an educational device of a maximum degree of usefulness in 20 kindergartens and elementary schools and is particularly adapted for use by children as an educational toy. By constructing the device as shown it may be folded compactly when not in use and thus readily stored in 25 a small space.

Various changes in the specific form shown and described may be made within the scope of the claims without departing from the spirit of my invention.

30 I claim:

1. An educational device in the form of a toy for small children comprising two sections foldably connected and adapted to be adjusted to an extended position to form 35 continuations of each other, a plurality of rungs removably mounted upon said sections and located at spaced intervals lengthwise thereof, apertured members having designations produced thereon and adapted 40 to be strung upon said plurality of rungs, said apertured members being adjustable on said plurality of rungs to group said designations in predetermined combinations and

means for supporting the extended sections in an upright position. 45

2. An educational device in the form of a toy for small children comprising parallel, side members, transverse members coöperating with said side members to hold the same in spaced relation with each other, said 50 side members being jointed, and, in conjunction with said transverse members, constituting foldable sections adapted to be adjusted to an extended position to form continuations of each other, said transverse 55 members comprising a plurality of rungs removably connected with said side members and located at spaced intervals lengthwise thereof and apertured blocks having designations produced thereon and adapted 60 to be strung upon said rungs, said apertured blocks being adjustable on said rungs to group said designations in predetermined combinations.

3. An educational ladder in the form of 65 a toy for small children comprising parallel and spaced side members, each consisting 70 of two sections hinged together and adapted to be adjusted to extended positions to form extensions of each other, a latch whereby the sections of said side members are fixed in their extended positions, a plurality of rungs removably connected with said side 75 members and located at spaced intervals lengthwise thereof, apertured cubical blocks having designations produced on the faces thereof and adapted to be strung upon said rungs, said blocks being adjustable upon said rungs to group said designations in predetermined 80 combinations and a prop pivotally connected with said side members for maintaining the extended ladder in an upright, inclined position.

In testimony whereof I have hereunto set my hand.

FRANCES AYRES RODDY.
